(57) **CLAIM**

The ornamental design for adjustable wrench, as shown and described.

DESCRIPTION

FIG. 1 is a perspective view of an adjustable wrench showing my new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof; and,

FIG. 8 is a second front view thereof showing the utilization of the adjustable wrench.

The broken lines shown in the drawings show unclaimed subject matter only and form no part of the claimed design.
